Primary Examiner—Janice E. Seeger*(74) Attorney, Agent, or Firm*—Marshall, Gerstein & Borun LLP(57) **CLAIM**

The ornamental design for a “canopy for a bassinet”, as shown and described.

DESCRIPTION

FIG. 1 is a perspective view taken from the right side and front showing my new design;

FIG. 2 is a right side elevational view, the left side elevational view being a mirror image thereof;

FIG. 3 is a perspective view taken from the right side and rear thereof;

FIG. 4 is a front view thereof;

FIG. 5 is a perspective view taken from the front and right side with the canopy in a down position;

FIG. 6 is a perspective view taken from the rear, right and above with the canopy in a down position; and,

FIG. 7 is a right side elevational view with the canopy in a down position, the left side elevational view being a mirror image thereof.

The broken lines showing a fastener and bassinet are for illustrative purposes only and form no part of the claimed design.
